UNITED STATES PATENT OFFICE.

ERNST HORN, OF BERLIN, GERMANY, ASSIGNOR TO SIEMENS & HALSKE AKTIEN-
GESELLSCHAFT, OF SIEMENSSTADT, NEAR BERLIN, GERMANY.

TELEPHONE SYSTEM.

Application filed September 7, 1923. Serial No. 661,444.

To all whom it may concern:

Be it known that I, ERNST HORN, a German citizen, and a resident of Kulmstrasse 16, Berlin, Germany, have invented certain new and useful Improvements in or Relating to Telephone Systems, of which the following is a specification.

In the known arrangements for metering calls of different values in telephone systems, the switching devices which move on a calling subscriber's meter an amount corresponding to the value of a call set up are connected up over the numerical switch that determines the direction in which the call is made, or these switching devices are so controlled by the trains of impulses for operating these numerical switches that these devices can operate the meters according to the direction in which the call is made. These known arrangements have the disadvantage that the devices for moving on the meters in telephone areas with main and sub-exchanges are located both in the large main exchanges and in the small sub-exchanges. These devices are relatively complicated, especially when duration recording is to be effected in addition to zone metering. Thus in the known arrangements all exchanges must be provided with auxiliary devices for instance special time switches, etc., in addition to the actual devices for moving on the meters.

The object of the present invention is to render possible a better and more economical arrangement of the devices for moving on the meters, this being achieved by centralizing these switching devices in the main exchanges, where they are preferably associated with the lines connecting the main exchanges with the sub-exchanges. In this case it is preferable to locate the metering devices in front of the first numerical switch if the calls originate in the sub-exchanges, and to locate them beyond the first numerical selection stage if the calls are made to sub-exchanges.

Since the traffic zones are determined mainly by the location of the calling and wanted exchanges quite independently of the connecting route, it is necessary in the known arrangements for the meter actuating devices at the different exchanges to have a construction and circuit arrangement according to the location of these exchanges.

Now another feature of the present invention is that the different switching members of the meter actuating devices at the main exchanges are all exactly alike without regard to the location of the different exchanges in the area, said members being connected with one another by auxiliary means, e. g. distribution strips, corresponding to the exchange with which they are associated.

This application also discloses various novel auxiliary switch circuit arrangements which are claimed in pending application, Serial No. 661,445, filed September 7, 1923.

The drawings show one example of the invention.

Figs. 1-3, inclusive, when laid out from left to right in the order named, diagrammatically show the necessary circuits for establishing a connection from a sub-exchange UA_1 , to a second sub-exchange UAX by way of the main exchange HA .

Fig. 4 shows the arrangement used in extending connections from lines in the main exchange.

Fig. 5 is a map or layout of the main and sub-exchanges illustrating the route taken and the distance for which the meters are operated.

Figs. 6 and 7 show the inter-connections which are made between the switches MS_2 and ZS_1 for the exchanges UA_1 and UA_2 , respectively.

In Fig. 8 are shown diagrammatically the connecting devices of a main exchange HA and of a sub-exchange UAI . Only a final selector (LW_4) and a subscriber's instrument, Tn_5 , are shown of a second sub-exchange UAX connected to the same main exchange.

A connection between the subscribers Tn_1 and Tn_2 belonging to the same sub-exchange UAI is set up as follows:

The preselecting devices $I.VW_1$ and $II.VW_1$ having been positioned, the first numerical switch $I.GW_1$ of the main exchange is connected up over the trunk line VL_1 to the main exchange HA . The train of impulses for operating this numerical switch also causes the auxiliary digit switches MS_1 in the sub-exchange UA_1 and MS_2 in the main exchange HA to be operated. The first group selector is, for instance, set on the third level, whereupon it takes into use a

free trunk line VL_2 to the second group selector $II.GW_1$.

Simultaneously with the positioning of the second group selector, the auxiliary digit switch MS_1 is also moved on by the calling subscriber. If now the number of impulses for setting this switch is such that the connection remains in the calling sub-exchange (UAI) the auxiliary digit switch MS_1 releases the trunk line VL_1 to the main exchange HA and thus also releases the first group selector $I.GW_1$ as well as the trunk line VL_2 and the second group selector $II.GW_1$. At the same time the second preselector $II.VW_1$ located in front of the auxiliary digit switch MS_1 is started up.

This preselector now takes into use a free trunk line VL_3 to a local final selector LW_1 , whereupon the latter is set on the contact to which the subscriber's line to instrument T_{n_2} is connected.

A connection between the subscriber T_{n_1} (UAI) and the subscriber T_{n_4} of the main exchange (HA) extends over the following connecting devices: $I.VW_1$, $II.VW_1$, Ue , VL_1 , (MS_2) ZS_1/ZS_2 , $I.GW_1$, LW_3 to the station T_{n_4} .

A connection between the subscriber T_{n_1} (UAI) and the subscriber T_{n_5} who is connected to the sub-exchange UAX located in the same traffic zone, extends over the following connecting devices and lines: $I.VW_1$, $II.VW_1$, Ue , VL_1 , (MS_2) ZS_1/ZS_2 , $I.GW_1$, VL_2 , $II.GW_1$, VL_4 and LW_4 to station T_{n_5} .

A connection between the subscriber T_{n_1} of the sub-exchange UAI and a subscriber of an exchange located in the traffic zone II extends over the following connecting devices and lines: $I.VW_1$, $II.VW_1$, Ue , VL_1 , (MS_2), ZS_1/ZS_2 , $I.GW_1$, (level 8) VL_5 , VL_6 , $II.GW_2$, VL_7 to the exchange in zone II.

A connection between the subscriber T_{n_3} of the main exchange HA and a subscriber of an exchange located in the traffic zone II extends over the following connecting devices: $I.VW_2$, $II.VW_2$, $I.GW_2$, VL_8 , ZS_1/ZS_2 , VL_9 , VL_6 , $II.GW_2$, VL_7 to the exchange in zone II.

The apparatus ZS_1/ZS_2 and ZS_1/ZS_2 ' comprises the switching devices for moving on the meters of the calling subscribers. It can be clearly seen from Fig. 8 that all these switching devices are located in the main exchange HA, thus those switching devices which are operated for outgoing calls from a sub-exchange are located in front of the first numerical switch in the connection, that is to say in the present case in front of the first group selector $I.GW_1$. Those switching devices (ZS_1/ZS_2 '), which are operated for calls from the main exchange are however located beyond the first numerical switch, namely between the latter ($I.GW_2$) and the second numerical switch $II.GW_2$. The second numerical switches ($II.GW_2$) are used

for all calls, that is to say for those outgoing from the main exchange subscribers as well as for those originated by sub-exchange subscribers. The meter operating devices ZS_1/ZS_2 ' are so arranged that they are not connected up for calls outgoing from a sub-exchange subscriber. This is achieved by providing separate first numerical switches for sub-exchange and main exchange subscribers and by connecting the meter operating devices ZS_1/ZS_2 ' to the lines VL_8 , VL_9 , which inter-connect the contacts of both selector groups $I.GW_2$, $I.GW_1$. Hence the trunk lines VL_5 , VL_6 from the contacts of the first group selectors for sub-exchanges ($I.GW_1$) lead direct to second group selectors $II.GW_2$, while the trunk lines VL_8 , VL_9 extend from the contacts of the first group selectors for the main exchange subscribers ($I.GW_2$) over the meter operating devices (ZS_1/ZS_2).

In Figs. 1 to 4 are shown the circuits concerned in setting up the different connections. A connection between the subscriber T_{n_1} of the sub-exchange UAI and the subscriber T_{n_5} of the sub-exchange UAX will first be explained, both these subscribers being in the same traffic zone.

When the subscriber T_{n_1} originates a call, the relay R_1 of the preselector $I.VW_1$ operates in known manner and causes this preselector to set itself on a free $II.VW_1$. When this has been done, the following circuit is established: earth, battery, contact $1r_1$, windings I and II of relay T_1 , wiper 2, contacts 3, $4t_2$, relay R_2 , earth. The relay T_1 in known manner stops the preselector, disconnects the calling relay R_1 at the contacts 5 and $6t_1$ and connects through the speaking leads a , b at the contacts 7 and $8t_1$. At the second preselector $II.VW_1$ the operated relay R_2 at contact $9r_2$ closes the circuit of the driving magnet D_1 and at contact $10r_2$ prepares the energizing circuit for the test relay T_2 . The circuit of the driving magnet extends as follows: earth, battery, contacts $9r_2$, $11u$, magnet D_1 , contacts $12d_1$, $13t_2$, earth. The following circuit is established when the second preselector $II.VW_1$ finds a free repeater Ue and associated therewith a free trunk line VL_1 leading to the main exchange HA: earth, battery, contact $10r_2$, windings I and II of relay T_2 , contact $14u$, wiper 15, contact 16, lead 17, contact $18s$, winding I of relay C_1 , contact $19v$, earth. The relays T_2 and C_1 operate. The relay T_2 at contact $13t_2$ opens the circuit of the driving magnet D_1 , at contact $15t_2$ short circuits its high resistance winding I and switches through the testing and blocking lead from the first preselector $I.VW_1$ to the repeater Ue and simultaneously disconnects the relay R_2 at contact $4t_2$. Furthermore at the contacts 20 and $21t_2$ the speaking leads are switched

through to the feeding bridge at the repeater U_e , which comprises the relays A_1 and B_1 whereupon both these relays operate.

At the repeater, the relay C_1 closes its contact 22 and thus prepares a holding circuit over its winding II. Furthermore at contact $23c_1$ the impulse contact $25a_1$ of relay A_1 is connected to the lead 24 of the trunk line VL_1 . The operated relay A_1 opens the contact $25a_1$, over which are given the impulses for setting the numerical switches, at contact $26a_1$ short circuits the relay V_2 while at the same time by opening contact $27a_1$ removing the short circuit from the winding II of relay C_1 and also opens the impulse contact $28a_1$ for the magnet D_2 of the auxiliary digit switch MS_1 . Among other circuit changes the relay B_1 opens its contact $29b_1$, thereby removing the short circuit round the winding I of relay V_1 . The latter operates, opens its contacts 19, 30 and $33v_1$ and closes its contacts 31 and $32v_1$. The closure of the contact $32v_1$ causes the rotary magnet D_2 of the auxiliary switch MS_1 , to be connected up: earth, contacts $32v_1$, $34v_2$, wiper 35, contact 36, magnet D_2 , (ms_1), battery, earth. The wiper 35 is moved on to the second contact 37 and thereby the following circuit is closed: earth, contacts $32v_1$, $34v_2$, wiper 35, contact 37, lead 38, winding 39 of the repeater, contact $40v_2$, lead 41 of the trunk line VL_1 , contacts $42c_2$, $43hr$, relay V_3 , winding I, contact 44 of the auxiliary switch MS_2 , wiper 45, resistance 46', battery, earth. The relay V_3 operates, opens its contact $46v_3$ and closes its contacts $47v_3$, $48v_3$, $49v_3$ and $50v_3$. At contact $48v_3$, the rotary magnet D_3 (ms_2) of the auxiliary digit switch MS_2 is connected to the impulse contact 51 of a relay A_2 , while at the contact $49v_3$ the first group selector of the main exchange is taken into use over the following circuit: earth, contact $49v_3$, relay C_2 , resistance 52, contact $53s_1$, lead 54, off normal contact $55k$ of the first group selector $I.GW_1$ winding I of relay B_2 , winding I of relay C_3 , battery, earth. The relays C_2 (Fig. 2) as well as B_2 and C_3 (Fig. 3) operate. The relay C_2 closes the contact $56c_2$ located in parallel with $49v_3$, opens the contact $42c_2$ and closes the contacts 57 and $58c_2$. At contact $57c_2$ the lead 41 is connected with the lead 59 to the first group selector $I.GW_1$, while at contact $58c_2$ the relay V_3 is maintained energized, after its original energizing circuit is opened at contact $42c_2$. The holding circuit extends as follows: earth, battery, resistance 46', wiper 45, contact 44, winding I of relay V_3 , lead 60, normal contact 61, wiper 62, contact $58c_2$, earth. At the first group selector $I.GW_1$ the relay C_3 by closing the contact $63c_3$ prepares a holding circuit over both its windings I and II, which becomes operative as soon as the contact $55k$ is opened at

the first step of the group selector. The relay B_3 at its contacts 64 and $65b_3$ connects the relay A_3 to the lead 66 and connects the winding II of relay B_3 to the lead 59. The impulses of the first train transmitted by the calling subscriber, besides operating the first group selector $I.GW_1$ located at the main exchange, also operate the auxiliary digit switch MS_2 located in front of this group selector and the auxiliary digit switch MS_1 in the sub-exchange. It will be assumed that for this connection only a single payment has to be made, since the sub-exchange UAX lies in the same traffic zone as the sub-exchange UAI . If for instance the first train of impulses comprises three impulses, then all the three numerical switches ($I.GW_1$, MS_1 , MS_2) are moved on three steps. The impulses are sent in known manner by interrupting the loop at the calling subscriber's station, so that the relays A_1 and B_1 release at each impulse and the relay A_1 closes its impulse contacts $25a_1$ and $28a_1$. The circuits for operating the different apparatus extend as follows:

1. for the auxiliary digit switch MS_1 in the sub-exchange: earth, contacts $32v_1$, $67f$, $28a_1$, 36, magnet D_2 , battery, earth. 2. for the impulse receiving relays A_2 (Fig. 2) and A_3 (Fig. 3) in the main exchange: earth, contacts $25a_1$ (Fig. 1) $23c_1$, lead 24, thence over relay A_2 , contact $50v_3$, resistance 68, battery, earth, and also thence over contact $69t_3$, lead 66, contact $64b_3$, relay A_3 , battery, earth.

The relay A_3 in known manner brings about the setting of $I.GW_1$ on the third level. The relay A_2 (Fig. 2) closes the circuit for the driving magnet D_3 (ms_2) as follows: earth, contact $51a_2$, winding II of relay V_3 , contact $48v_3$, magnet D_3 (ms_2), battery, earth. Hence at the end of the train of impulses the wipers 45 and 62 of the auxiliary digit switch MS_2 stand on the contacts 70 and 71 respectively. When the relay V_3 has released, it cannot be again energized during the further setting up of the connection. It should however here be noted that as soon as the relay C_2 is energized, the relay U_2 is also energized as follows over its winding I: earth, contact $72c_2$, winding I of relay U_2 , contact $73hr$, driving magnet D_4 of the counting switch ZS_2 , battery, earth. The magnet D_4 is not energized owing to the high resistance of winding I of relay U_2 . The relay U_2 has therefore opened its contact $74u$ and thereby prevents the magnet D_3 (ms_2) being connected up after relay V_3 releases.

The transmission of the first impulse from the calling station and the opening of the contact $26a_1$ by the impulse receiving relay A_1 , causes the removal of the short circuit round the winding I of relay V_2 . Hence relay V_2 can operate and it opens its con-

tacts $34v_2$ and $40v_2$ and closes the contact $74v_2$. Battery is thereby connected over resistance 75 to the lead 41 of the trunk line VL_1 and the relay B_3 (Fig. 3) is thereby maintained energized over its winding II as follows: earth, battery, resistance 75, contact $74v_2$, lead 41, contact $57c_2$, normal contact 76 and wiper 77 of the switch ZS_2 , junction point 78, contact $79t_3$, lead 59, contact $65b_3$, winding II of relay B_3 , earth. The relay B_2 is also connected to the junction point 78 (Fig. 2). It is, however, of high resistance and is so much shunted by the winding II of relay B_3 (Fig. 3) that it cannot operate.

The first group selector $I.GW_1$ in known manner hunts for a free trunk line VL_2 and the connection is completed by the positioning of the other numerical switches (e. g. the $II.GW_1$ and LW_4 shown in Fig. 3.)

It is assumed that the final selector LW_4 is provided with a side switch and that the impulse relays A_5 and B_5 are disconnected after the transmission of the trains of impulses for operating the driving magnets. It is also assumed that position 13 is the speaking position of the side switch, into which it goes after the wanted subscriber T_{n_5} has answered and in which position a feeding relay Y for the subscriber T_{n_5} is connected up. In position 13 of the side switch, battery is connected to the lead 82 over a resistance 80 and the side switch contact 81, so that the relay B_2 in Fig. 2 is energized as follows: earth, battery, resistance 80, side switch contact 81 (position 13), lead 82, contact 83 and wiper 84 of the second group selector $II.GW_1$, contact $85p_2$, contact 86 and wiper 87 of the first group selector $I.GW_1$, contact $88p_1$, lead 59, contact $79t_3$, junction point 78, relay B_2 , earth. The relay B_2 operates and causes the switch ZS_2 to move on to the next contact since the circuit for the driving magnet D_4 ($zsII$) is closed as follows: earth, interrupter 89, contact $90b_2$, off normal contact $91kzsII$ of the switch ZS_2 , magnet D_4 ($zsII$), battery, earth. Hence the wiper 77 of ZS_2 is moved to the contact 92. The magnet D_4 cannot be again operated, since the contact $91kzsII$ has now been opened. The relay B_2 furthermore at its contact $93b_2$ connects earth to the relay A_2 . In addition the relay S_1 is connected over contact $104b_2$ to the lead 54. The relay S_1 operates, opens its contact $53s_1$ and closes its contacts $99s_1$ and $112s_1$. At the contact $112s_1$ the relay U_2 is maintained energized over its winding II. To return now to the circuit changes, which take place in the calling sub-exchange UAI: it has already been described how the first train of impulses, which operated the first group selector $I.GW_1$, also moved on the digit switch MS_1 for instance to the

contact 94. At the end of this train of impulses, the relay U_1 is energized as follows: earth, contacts $32v_1$, $34v_2$, wiper 35, contact 94, relay U_1 , contacts $119f$ and $120c_1$, battery, earth. The relay U_1 connects itself in a holding circuit at its contact $121u_1$; this circuit can, however, only be closed so long as local connecting devices LW_1 accessible from the preselector $II.VW_1$ are free, since only in this case is the contact $122g$ closed. The second train of impulses for setting the second group selector $II.GW_1$ causes the driving magnet D_2 (ms_1) of the digit switch MS_1 to be operated in the same manner as did the first train of impulses. Thereby the wiper 35 reaches for instance the contact 118. After the release of relay V_2 due to the prolonged short circuit of its winding I at contact $26a_1$, the relay F is energized: earth, contacts $32v_1$, $34v_2$, wiper 35, contact 118, windings I and II of relay F , battery, earth. The relay F closes its contact 95 and thereby connects itself in a holding circuit dependent on the contact $96v_1$ of the slow releasing relay V_1 . Furthermore the relay F opens the contact $67f$, so that the rotary magnet D_2 (ms_1) cannot be operated further by other trains of impulses.

If at the end of the conversation the wanted subscriber is the first to hang up, the side switch of the final selector LW_4 reaches the position 14. The circuit for the relay B_2 (Fig. 2) is however maintained, since in this position also the contact 81 (Fig. 3) is closed. When the calling subscriber T_{n_1} (Fig. 1) also hangs up his receiver, the relay A_1 is permanently de-energized, hence the contact $26a_1$ remains open and the contact $27a_1$ remains closed. The winding II of relay C_1 is short circuited, and the relay C_1 therefore releases. Among other circuit changes, it opens its contacts 22 and $23c_1$, and closes its contacts 97 and $98c_1$. The circuit of winding I of the slow acting relay V_1 is opened at contact $22c_1$. At contact $97c_1$ however the following circuit is closed: earth, battery, winding II of relay V_1 , contact $97c_1$, lead 24, winding I of relay A_2 , contact $93b_2$, earth, so that the relay V_1 remains energized in this circuit. The relay A_2 also operates and gives a metering impulse to the meter impulse repeating relay ZR at the repeater Ue of the exchange UAI over the following route: earth, battery, contacts $99s_1$, $100a_2$, relay HR , contact $57c_2$, lead 41, contacts $40v_2$, $98c_1$, relay ZR , contact $31v_1$, earth. The relay ZR closes its contact $101zr$ and thereby connects the low resistance 102 in parallel with the high resistance 103 to the lead 17 coming from the second preselector $II.VW_1$. Thereby the current flowing over the meter Z at the first preselector $I.VW_1$ is increased to such an extent that the meter can operate and the conversation can be metered. After the relay HR has

been energized, the driving magnet D_4 (zsII) of the switch ZS_2 is energized as follows: earth, contacts $51a_2$, $105hr$, magnet D_4 , (zsII) battery, earth. The relay HR 5 at its contact $106hr$ short circuits the relay A^2 , hence it releases. The wiper 77 is moved on one step by the magnet D_4 and reaches the contact 107. The relay B_2 is now short circuited because earth is connected 10 to the junction point 78 over the contact $58c_2$, wiper 62, the contacts 71 and 107 and the wiper 77. The relay B_2 releases and opens the contacts 93 and 104. The opening 15 of contact $104b_2$ interrupts the holding circuit over the relays C_2 , S_1 and C_3 , and the first group selector IGW_1 as well as the succeeding switches are released in known manner. When the contact $93b_2$ is opened, the relay V_1 at the repeater Ue is de-energized and releases. 20

The digit switches MS_1 and MS_2 as well as the counting switch ZS_2 are released in the following manner:

After the release of relay V_1 , the relays 25 V_2 and S are energized in the following route: earth, contact $33v_1$, winding II of relay V_2 , off normal contact $107kms_1$ of the digit switch MS_1 , winding II of relay S , battery, earth. Both the relays S and V_2 30 operate and close their contacts $108v_2$ and $109s$. Thereby the following circuit is closed for the rotary magnet D_2 (ms_2): earth, contacts $110v_1$, $109s$, $108v_2$, $67f$, $28a_1$, 36 , magnet D_2 , battery, earth. The magnet D_2 operates, 35 moves on the digit switch and at its contact $111d_2$ short circuits the relay V_2 . The relay V_2 releases and opens its contact 108, whereby the magnet D_2 releases and opens the contact 111. The relay V_2 now again operates, 40 and again closes the contact $108v_2$. This cycle is repeated until the auxiliary digit switch reaches its normal position, wherein the off normal contact $107kms_1$ is opened. After the release of the rotary magnet D_2 it 45 is impossible for the relay V_2 to again energize.

The relay U_2 in Fig. 2 was, as already mentioned, maintained energized during conversation over a contact 112 of relay S_1 50 and its winding II. Since the relay S_1 was de-energized after the release of relay B_2 , the relay U_2 is also de-energized and closes the following circuit for the magnet D_3 (ms_2): earth, battery, magnet D_3 , contact $46v_3$, off normal contact $113kms_2$ of the digit switch MS_2 , contact $74u_2$, winding II of relay HR , earth. The magnet D_3 operates and closes the following circuit: 55 earth, battery, winding II of relay U_2 , contact $114d_3$, winding III of relay HR , earth. The relay U_2 at contact $74u_2$ opens the circuit of the magnet D_3 , whereupon the magnet releases and opens the circuit of the relay U_2 . This cycle is repeated 60 until the digit switch reaches its normal po-

sition, in which the contact $113kms_2$ is opened.

The switch ZS_2 is moved into its normal position at the same time as the digit switch MS_2 , since the circuit of driving magnet D_4 70 (zsII) is closed as follows: earth, battery, magnet D_4 , off normal contact $115kzsII$, normal contact $116kzsI$, contact $117u_2$, winding II of relay HR , earth. The magnet D_4 also closes a contact $118d_4$ in the circuit of 75 winding II of relay U_2 , so that the moving on of the switch ZS_2 is dependent only on the operation of the magnet D_4 and the relay U_2 . The driving circuit for the magnet D_4 is finally opened when the switch ZS_2 80 reaches its normal position since the contact $115kzs_2$ is then opened.

Consideration will now be given to the case when a connection is set up with a subscriber who is connected to an exchange located in a different traffic zone. Exchanges for which a zone payment has to be made are, for instance, reached over the eighth level, of the first numeral switch. Hence the first group selector is set on the eighth 85 level, in which it takes into use a free trunk line VL_5 . The continuation of the trunk line VL_5 is indicated by VL_6 in Figure 3. At the point (200, 201, 202) where these two lines meet, a trunk line VL_9 is connected 90 coming from the bank contacts of those first numerical switches (IGW_2) that are accessible to subscribers of the main exchange. Between the contacts 203, 204, and 205 at the last mentioned first numerical 95 switch IGW_2 and the meeting points 200, 201 and 202 are located the meter operating devices that are only operated for calls originated by the main exchange subscribers. These meter operating devices (MS_3 , ZS_1 , $/ZS_2$) are therefore not employed for the 100 present connection. When the first group selector IGW_1 is set on the eighth level, the digit switch MS_1 is at the same time set on to the eighth contact, which is for instance the contact 118. After the relay V_2 105 has released, the relay F is energized as before and prevents the rotary magnet D_2 being operated by further trains of impulses. 110

The wiper 45 of the digit switch MS_2 is 115 likewise set on to the eighth contact, which in Fig. 2 is designated by 121. The winding III of relay HR is short circuited for the duration of the impulse train by the contact $47v_3$. The relay HR is however 120 energized upon the release of the relay V_3 : earth, battery, resistance $46'$, wiper 45, contact 121, relay HR , winding III, earth. The relay HR operates and by opening the contact $73hr$ interrupts the circuit over the 125 winding I of relay U_2 . The relay U_2 releases and closes the contact $74u_2$ whereby the following circuit is closed for the magnet D_3 : earth, battery, magnet D_3 , contacts $46v_3$, $113kms_2$, $74u_2$, relay HR , winding II, 130

- earth. The magnet D_3 by closing its contact $114d_3$, energizes the relay U_2 over its winding II in series with the winding III of relay HR. The relay U_2 operates, and opens the contact $74u_2$, whereby the circuit for the magnet D_3 is opened, so that it de-energizes and opens the contact $114d_3$. Thereupon the relay U_2 releases and closes contact $74u_2$. This cycle is repeated until 10 the wiper 45 reaches the contact 122. This contact cannot be reached by the first train of impulses transmitted by the calling subscriber which will never exceed ten. As soon as the wiper 45 reaches the contact 15 122, the following circuit is established: earth, battery, resistance 46', wiper 45, contact 122, winding I of relay V_3 , lead 60, contact 123, wiper 62 contact $58c_2$, earth. The relay V_3 operates, opens the circuit for 20 the automatic rotation of the digit switch MS_2 by opening the contact $46v_3$, and at contact $48v_3$ connects the rotary magnet D_3 to the impulse contact $51a_2$. The digit switch MS_2 has now been brought into a position 25 in which it can be operated by the second train of impulses. The transmission of the second train of impulses causes the relay A_2 to be operated in the manner already described and the relay at its contact $51a_2$ sets 30 the rotary magnet D_3 in operation. The circuit of the rotary magnet D_3 contains the winding II of relay V_3 , so that this relay remains energized for the duration of the 35 train of impulses. The energization of the relay V_3 after the switch 45 has been set on the contact 122 also causes the relay HR to release, thus preventing the rotary magnet D_4 of the switch ZS_2 being operated by the 40 relay A_2 . Let it be assumed that the second train of impulses comprises only a single impulse and hence the wiper 62 of the digit switch MS_2 has been set on the contact 124, over 45 which is connected up thereafter wiper 125 of the zone switch ZS_1 . After the connection has been set up and the wanted subscriber has answered in the manner already described, the relay B_2 is 50 energized and causes the switch ZS_2 to take one step as before; hence the wiper 77 of ZS_2 stands on contact 92. Furthermore the contacts 126 and 127 are closed in this position of ZS_2 . The relay S_1 has been again 55 operated over the contact $104b_2$ in the manner already described and has connected up the relay U_2 over its winding II so that the contact $128u_2$ is opened and the contact $129u_2$ is closed. The meter operating device has a time 60 switch associated with it, which is moved on by the magnet D_5 at fixed intervals of time. After the contact $129u_2$ has been closed, the time switch is moved out of its 65 normal position since the magnet D_5 is energized as follows: earth, interrupter 130,

contacts $131b_2$, $1262s_2$, normal contact $132ze$, contact $129u_2$, rotary magnet D_5 (ze), battery, earth. At the first step of the time switch Ze the contact $132ze$ is opened and the contact $133ze$ is closed. 70

It is assumed in the present example that the time switch has 36 contact positions and is moved on by a time contact $134uk$, which is closed every 5 seconds; it may for instance be operated by an electric clock. Hence one rotation of the time switch corresponds to a duration of 3 minutes, which has been assumed to be a unit of time for the calls. The contact 134 is closed shortly before the time switch has completed a rotation. 75 Thereby the corresponding subscribers are given a buzzer tone, from which they recognize that a 3 minute period will be completed in a few seconds and that further charge will be made if the conversation is continued. The circuit for repeating the signal, which is closed upon the closure of the contact, extends as follows: earth, secondary winding of the induction coil 135, contact $136t_3$, wiper 137, contact $134ze$, winding II of relay B_2 , winding II of relay A_2 , earth. The buzzer tone is repeated from the windings II of the relays A_2 and B_2 to the windings I of these relays and can therefore be heard by the subscribers. When the time switch upon its rotation reaches the last contact (the 36th) the driving magnet D_6 of the zone switch ZS_1 is energized as follows: earth, 135, contact $136t_3$, wiper 137, contact $138ze$, magnet D_6 (ze_1), battery earth. The zone switch ZS_1 is moved on one step. The circuit changes just described are repeated at each rotation of the time switch Ze . 95

The zone switch ZS_1 , which is controlled by the time switch Ze , has its contacts connected with the contacts of the counting switch ZS_2 . The wiper 125 of ZS_1 is connected up for calls to the second traffic zone. The normal contact 139 is connected with the fourth contact 140 of the switch ZS_2 . Since this switch is set on the first contact 92 as already mentioned, it has to take three steps before the wiper 77 reaches the contact 140. Hence for connections in the traffic zone II, three metering impulses have to be transmitted for each conversation unit. When the zone switch ZS_1 has been advanced one step at the end of the first unit of time, the wiper 125 stands on the contact 141 which is connected with the seventh contact 142 of ZS_2 . 110 115 120

For calls to the traffic zone III the wiper 143 is connected up, as has been assumed in Fig. 2. The normal contact 144 upon which this wiper is standing, is connected to the sixth contact 145 of ZS_2 . Hence for calls to the third traffic zone five impulses are transmitted for each time unit. 125

For calls to the fourth traffic zone, for 130

which the wiper 146 of ZS_1 is connected up, seven metering impulses have to be transmitted for each time unit, and for calls to the fifth traffic zone nine metering impulses have to be transmitted.

In the present system, devices are also provided for limiting the duration of the different calls according to their value. This is achieved by means of the switch ZS_2 . In the present example this switch has 32 positions. The last five contacts 147 to 148 are multiplied together and are connected with a relay T_3 . Since the zone switch ZS_1 is always moved on one step at the end of a three minute period, the wiper 125 of the zone switch ZS_1 reaches the ninth contact 149 at the expiration of 8 time units in the case of calls to the traffic zone II; the contact 149 is connected to the contact 147 of the switch ZS_2 . When the call has lasted so long, i. e. 24 minutes, the relay T_3 is energized in the following circuit: earth, contact 58c₂, wiper 62, contact 124, wiper 125, contact 149, lead 150, contact 147, relay T_3 , battery, earth. The relay T_3 operates, opens its contact 136 and connects the buzzer tone at its contact 151 to the windings II of the relays A_2 and B_2 . The calling subscriber therefore immediately receives the buzzer tone. In addition however the contacts 69 and 79t₃ are also opened and the contact 152t₃ is closed, hence the speaking connection is interrupted. Nevertheless, however, the relay B_2 is maintained energized over the contact 152t₃ and the resistance 68.

If a connection has been set up to the traffic zone V, then the wiper 62 of the digit switch MS_2 stands on the contact 153, so that the wiper 154 is connected up. The normal contact 155 of this switch is connected with the tenth contact 156 of the switch ZS_2 . It is assumed that for a connection of such high value the maximum duration of a conversation is two units of time. The wiper 154 of the switch ZS_1 is at the end of the first time unit moved on to the contact 157, which is connected with the contact 158 of ZS_2 . At the end of the second time unit the driving magnet D_6 of ZS_1 again receives an impulse and the wiper 154 reaches the contact 159, which is connected with the contact 160 of ZS_2 . The relay T_3 is then at once energized and brings about the circuit changes already described.

When the calling subscriber hangs up his receiver at the end of a conversation in one of the traffic zones II to V, the relay A_2 is energized as already described and transmits a metering impulse over the lead 41 to the metering repeat relay ZR in Fig. 1. Thereby the relay HR is again energized, and by closing the contact 105 connects the driving magnet D_4 of ZS_2 to the impulse contact 51a₂. The relay HR at its contact

106hr short circuits the relay A_2 , so that the relay A_2 slowly releases and opens the contact 51a₂ in the circuit of the magnet D_4 and also the contact 100a₂ in the circuit of relays HR and ZR .

The magnet D_4 releases and after a little while the slow acting relay HR also releases. Thereupon the relay A_2 again operates and causes the transmission of a second metering impulse and the moving on of the switch ZS_2 . This cycle is repeated until the wiper 77 reaches a contact, over which the relay B_2 is short circuited. If the zone switch ZS_1 was moved on three times during a conversation in the second traffic zone, the wiper 125 stands on the contact 161, which is connected with the contact 162 of the switch ZS_2 . When the wiper 77 reaches this contact, the relay B_2 is short circuited, since earth is connected to the wiper 77 over the contact 58c₂, wiper 62, contact 124, wiper 125, contacts 161 and 162. The relay B_2 releases, opens contacts 93 and 104b₂, whereby the relays C_2 and S_1 are permanently de-energized.

As soon as the transmission of metering impulses commences, the contact 127z₂ was opened, this contact being closed only in the first position of the switch ZS_2 , that is when the wiper 77 stands on the contact 92. Thus the operation of the time switch Ze is prevented during meter impulse transmission.

The switches MS_2 , ZS_1 and Ze are moved on into their normal position when the relay C_2 is de-energized after the release of relays B_2 and S_1 . The moving on of the time switch Ze is effected by the alternate operation of the driving magnet D_5 and the relay U_2 . The circuit of the driving magnet D_5 of the time switch Ze is closed over: earth, battery, magnet D_5 , contact 128u₂, off normal contact 170kze, relay HR , winding II, earth. The magnet D_5 closes its contact 171d₅ and thereby energizes the relay U_2 , which opens the contact 128u₂, so that D_5 is de-energized. The relay U_2 is now de-energized and again closes its contact 128u₂, so that the magnet D_5 receives another impulse. The contact 170kze is opened when the time switch Ze reaches its normal position. The circuit for driving magnet D_6 of the zone switch ZS_1 is closed over: earth, battery, magnet D_6 , contacts 172kzs₁, 117u₂ winding II of relay HR , earth. The magnet D_6 energizes the relay U_2 over its contact 173d₆. The contact 172kzs₁ is opened when the zone switch ZS_1 reaches its normal position and the magnet D_6 cannot again be energized. The circuits for the magnets D_3 and D_4 , which move the digit switch MS_2 and the zone switch ZS_2 respectively into the normal position, have already been previously described.

The trunk line VI cannot be taken into

use so long as any of the switches MS_2 , ZS_1 or ZS_2 remain in the operated condition. This is due to the relay HR which at its contact 146 closes a circuit for the relay 5 S at the repeater Ue (Fig. 1). As already mentioned, the relay S is energized over the off normal contact 107 kms_1 during the releasing motion of the digit switch MS_1 . When the digit switch MS_1 reaches its normal 10 position, the contact 107 kms_1 is opened and the contact 175 kms_1 is closed. If at this time the relay HR in Fig. 3 is still energized, the relay S is maintained energized as follows: earth, resistance 176, contacts 146 hr , 42 c_2 , lead 41, contact 175 kms_1 , relay S , battery, earth. The relay S therefore maintains its contact 18s open, so that it is impossible for the trunk line VI_1 to be taken into use by a testing second pre- 15 selector $II.VW_1$.

If a call is set up between the subscriber Tn_3 of the main exchange HA , (Fig. 4) and a subscriber of an exchange accessible over the trunk line VL_6 , the relays C_6 , A_6 and B_6 , 20 are energized after the preselecting devices IVW_2 (Fig. 4) and $II.VW_2$ have been positioned. Thereafter in known manner the first numerical switch $I.GW_2$ is set on a level to which the trunk line VL_6 is connected. 25 When such a free trunk line has been found, the following circuit is established: earth, windings I and II of relay P_s , contact 206 v_s , wiper 207, contacts 205 and 208 v_s , relay C_7 , lead 209 of the trunk line VL_9 , junction 30 point 202, lead 210 of the trunk line VL_6 to battery over switching devices of the selectors in the distant exchange. The relay C_7 closes the contact 211 c_7 located in parallel with the contact 208 v_s and energizes the 35 relay V_s over the contact 212 c_7 , the contact 213 of the digit switch MS_3 and the wiper 214. Relay V_s opens the contact 208 v_s and at contact 215 v_s connects the relay A_7 to battery over the resistance 216. Between 40 the trunk lines VL_8 and VL_9 lie the switching members of the meter operating devices, comprising the switching devices MS_3 , ZS_1' and ZS_2'' . The method of operating these 45 meter operating devices corresponds to that shown in Fig. 2, so that it is unnecessary to describe the circuit changes. The relay B_7 corresponds to the relay B_2 and the relay T_4 corresponds to the relay T_3 .

It can be seen from Fig. 3 that all the 50 meter operating devices are concentrated in the main exchange HA . The value of the connection is determined by the location of the calling and wanted exchanges. Now Fig. 5 shows the position of the exchanges 55 in a telephone area. HA is again the main exchange, to which are connected the sub-exchanges UAI — $UAVI$. Calls between subscribers connected to different sub-exchanges are always set up over the main exchange. 60 65 Nevertheless the charge made is based only

on the distance between the two sub-exchanges for instance between the exchanges UAI and UAI . From the exchange UAI the other sub-exchanges lie in the following traffic zones: UAI in the zone II, exchanges UAI and $UAVI$ in the zone III, UAV and UAV in the zone IV. From the exchange UAI however, the exchanges UAI and UAI lie in the zone II, exchange UAV in the zone III and UAV and $UAVI$ in the zone IV. Although the digit switches, for instance, for a call to the sub-exchange UAV , must always be set on the same contact, the meter operating devices in the main exchange must be operated in a different manner according to whether a call originates in the exchange UAI or in the exchange UAI . It would therefore be necessary to provide special meter operating devices for each sub-exchange. This defect is 85 however avoided by inserting auxiliary devices between the individual switching members of the meter operating devices, these auxiliary devices serving to make the meter operating devices suitable for the incoming traffic direction, because this direction determines the location of the calling exchange. The lines leading from the contacts of the digit switches MS_2 (or MS_3) to the wipers of the zone switch ZS_1 (or ZS_1') are taken over the distribution strips VL_e , as can be seen from Figs. 6 and 7. These distribution strips are also shown in Fig. 2 by thick lines, but were not taken into consideration when describing the circuit changes. 90 95 100

Now Fig. 6 shows the connection between the auxiliary digit switch MS_2 and the zone switch ZS_1 of the meter operating devices, which are associated with the sub-exchange UAI . Now the sub-exchange UAI , having the calling number 81, lies in the second zone of the sub-exchange UAI ; hence the wiper 125 of the zone switch ZS_1 is connected with the contact 124 of the auxiliary digit switch MS_2 , this being effected over the contacts 400 and 401 by the distribution strip 300. The traffic zone III contains the sub-exchanges UAI and $UAVI$, having the call numbers 82 and 85, hence the contacts 224 and 225 are connected over the contacts 402, 403, 404 and the distribution strips 301 and 302 to the wiper 143 of the zone switch ZS_1 . The contacts 226 and 227 of the auxiliary digit switch MS_2 onto which the wiper 62 is set for connections in the sub-exchange UAV and $UAVI$, are connected with the wiper 146 of the zone switch ZS_1 over the contacts 405, 406 and 407 and the distribution strips 303 and 304. 105 110 115 120

Fig. 7 shows the connection of the auxiliary digit switch MS_2 with the zone switch ZS_1 for the meter operating devices associated with the sub-exchange UAI . The contact 224 of MS_2 , upon which the wiper 62 is set for calls to the sub-exchange UAI , 125 130

is likewise connected with the contact 403; it is however connected by means of a cross connecting wire 300' to the contact 400 instead of to contact 402, so that contrary to Fig. 6 the contact 224 is connected to the wiper 125 of the zone switch ZS_1 instead of to the wiper 143. The other contacts of the auxiliary digit switch are in a similar manner connected with the wipers of the zone switch ZS_1 as determined by the location of the sub-exchange UAII.

What I claim is:

1. In a measured service telephone system, a main exchange, a plurality of sub-exchanges, trunking facilities enabling the establishment of talking connections between lines of any two sub-exchanges via said main exchange, meters for the calling lines, and means at the main exchange for operating the meter of a calling line at the termination of a call a number of times dependent on the duration of the call.

2. In a measured service telephone system, a main exchange, a plurality of sub-exchanges, trunking facilities enabling the establishment of talking connections between lines of any two sub-exchanges via said main exchange, meters for the calling lines, and means at the main exchange for operating the meter of a calling line a number of times dependent on the value of the connection and the duration of the call, the said meter operating means being rendered effective only after the receiver has been replaced on its switch-hook.

3. In a measured service telephone system, comprising a main exchange and a plurality of sub-exchanges, meter controlling devices at the main exchange, means for causing one of said devices to prepare a meter operating circuit incidental to the process of setting up a connection between lines of two sub-exchanges, said device rendered effective at the termination of the call to operate a meter a number of times dependent on the duration of the talking connection.

4. In a measured service telephone system, a main exchange, a plurality of sub-exchanges, subscribers' lines terminating in said exchanges, meters for said lines, trunk lines common to all the subscribers' lines, numerical switches individual to the subscribers' lines of the sub-exchanges and having access to said trunk lines, other numerical switches individual to the lines of the main exchange, meter control apparatus for operating the meters of the sub-exchange lines located in front of the associated numerical switches, and other similar meter control apparatus in the main exchange for operating the meters of the lines in the main exchange located beyond the associated numerical switch.

5. In a measured service telephone system, a calling line in one exchange, a called line

in a second exchange, electro-mechanical means for establishing a talking connection between said lines, a meter for the calling line, means responsive to the setting up of a connection for determining the minimum number of times the meter of the calling line will be operated if the called subscriber responds, and means automatically operated periodically during the time the connection is maintained to re-determine the minimum number of times the meter will be operated.

6. In a measured service telephone system, a calling line in one exchange, a called line in a second exchange, electro-mechanical means for establishing a talking connection between said lines, a meter for the calling line, means responsive to the setting up of a connection for determining the minimum number of times the meter of the calling line will be operated if the called subscriber responds, and means responsive to the replacement of the receiver at the calling line for causing the operation of the meter as last predetermined.

7. In a measured service telephone system, three exchanges, a calling and a called line in the first and third respective exchanges connected via the second exchange, a meter for the calling line, meter control equipment located exclusively at the second exchange, means for setting said equipment to cause the meter to be operated a definite number of times if the established call is terminated within a predetermined period, and auxiliary means periodically effective after the lapse of such period for changing the meter control equipment to cause the same to operate the meter a greater number of times following the termination of the call.

8. In a zone metering telephone system, a directly controlled meter control switch operated during the setting up of a connection to select a bank contact individual to the particular zone called, a time controlled automatic switch, conductors of said zone selecting switch extending via wipers of said time controlled switch and a distributing frame intermediate to said switches so that the different switches of the different calling sub-exchanges may be each operated in the same manner to prepare charging circuits of different values when connections are set up to the same called sub-exchange.

9. In a measured service telephone system, a calling and a called line, means including an impulse repeating relay and automatic switches controlled thereby to establish a talking connection between said lines, a meter for the calling line, and means for causing said impulsing relay to automatically repeat impulses to said meter.

10. In a measured service telephone system, a calling and a called line, means including an impulse repeating relay and automatic switches controlled thereby to estab-

lish a talking connection between said lines, a meter for the calling line, and means for causing said impulsing relay to automatically repeat impulses to said meter, the number of impulses repeated to said meter depending on the duration of the call and the value of the connection.

11. In a measured service telephone system, a meter control switch, directly controlled automatic switches for use in setting up talking connections between subscribers' lines, said meter control switch also operative responsive to one or more series of im-

pulses transmitted to said automatic switches to predetermine the charge or rate of charge to be made for a connection, and means for causing said meter control switch to automatically operate a predetermined distance to render the same again under control of each of the impulses of the succeeding series transmitted to one of said automatic switches to determine the lapse time rate of charge to be made for the connection.

Signed by me at Berlin, Germany, this 17th day of August 1923.

ERNST HORN.
